UNITED STATES PATENT OFFICE.

WILLIE GRAHAM, OF HOUSTON, TEXAS.

REENFORCED CONCRETE TIE.

Application filed October 15, 1923. Serial No. 668,743.

This invention relates to railroad ties and more especially to ties of the reenforced concrete type such as shown in my Patent No. 1,406,454 dated February 14, 1922.

5 The objects of this invention are to provide a reenforced concrete tie of superior strength, elasticity and resilience and having a unique means for fastening the rails and maintaining the gauge. Another object 10 is the provision of a novel cushion block arranged between the rail and the tie.

The tie is so shaped that adjacent ties abut under the rails thus giving almost continuous support to the rails. The tie being narrow in the center a space is thus provided to retain the ballast and prevent it from scattering. The narrow ends of the ties, provide spaces between the ties for tamping. The bottom of the tie is concave in a longitudinal direction to provide drainage.

The above and further novel features will be more apparent from the following description taken in connection with the drawings, wherein—

25 Fig. 1 is a plan view of a railroad track using my novel ties, with certain parts broken away to show those beneath;

Fig. 2 is a central longitudinal vertical section through a portion of a tie, showing 30 the rail in place;

Fig. 3 is a transverse section taken on line 3—3 of Figure 2;

Fig. 4 is a transverse section taken on line 4—4 of Figure 1;

35 Fig. 5 is a perspective view of one end of a tie, the remaining portion being broken away to show the reenforcing rods, etc.;

Fig. 6 is a perspective view of a tie plate;

Fig. 7 is a perspective view of an inner 40 rail clip.

Fig. 8 is a detail of a modification of the bolt head holding means.

As shown in the drawings the tie embodies a straight central section A and enlarged end sections B. The tie is of monolithic concrete construction suitably reenforced throughout by longitudinal reenforcing bars 1 and additionally in the end sections by transverse bars 2 contacting with the longitudinal bars. These reenforcing bars are arranged in several layers as is customary in concrete construction in order to provide suitable reinforcement throughout the tie.

55 The cross-section of the central portion of the tie is generally rectangular with the up-

per corners chamfered off, as shown in Figure 5.

Each end section of the tie is provided with a rectangular portion 3 slightly below the top of the central section and the centers of these portions are properly spaced longitudinally of the tie a distance equal to that between the rails. Between the portions 3 and the central section of the tie there are integral fillets 4 to strengthen the junction points. Beyond the rectangular portions 3 are the tapered ends 5 shaped as shown in Figures 1 and 5.

The rectangular portions 3 are each provided in its top with a rectangular central recess 6 of uniform depth for the reception of a cushion block 7, which provides the necessary resilient support for the rail and prevents the transmission of shock to the tie and the resultant breakage. It also imparts easier riding qualities to the roadbed. This cushion block is a very important feature of my invention. It is composed of rock asphalt and I have discovered by practical tests that such blocks have many advantages over blocks composed of any other material. The block is prepared by crushing and grinding the rock asphalt and finally pressing in a suitable die to the proper shape and hardness. It has been determined that a block of the size shown prepared by this process resists a crushing load of more than nine times that applied by the heaviest locomotive in passing over a rail supported by these blocks set in my concrete ties.

To provide for wear of the cushion block, and to allow for its full cushioning effect, the end walls of the recess 6 are cut away as shown at 6' for a depth of about one-half an inch and for a width somewhat greater than the base of a rail. This absolutely prevents the rail from seating on the concrete and insures a resilient mounting at all times.

Rock asphalt such as I prefer to use is known as "Uvalde rock asphalt" and is mined in Uvalde, Texas.

This particular material contains certain mineral oils which are practically indestructible. These oils maintain the cushion blocks resilient under all conditions and prolong their life indefinitely.

In order to properly fasten the rails to my tie I have developed the following construction, best shown in Figures 2, 3 and 8. Below each cushion block the tie is provided with two longitudinally disposed slots 8.

At the bottom of the tie the edges of each pair of slots are reenforced by a pair of bars 9 having inturned ends 10. The surfaces of these bars are flush with the lower face of the tie and are deeply grooved or corrugated transversely as shown in Figure 2. Through the slots 8 are adapted to be passed the T-heads of bolts 11. The shanks of these bolts are cylindrical and suitably threaded at the end to receive nuts 12. For a short distance above the head, the shanks of the bolts are of square cross section as shown at 13, and the sides of the T-heads facing upwardly are corrugated corresponding to the corrugations in bars 9. After the tie has been laid the T-heads of the bolts may be inserted in the slots and the bolts pushed through the tie until the round portion of the shank is through the bars 9 when the bolt can be rotated 90° and the head drawn up against the bars 9 when the squared portion 13 fitting through the bars 9 will prevent any rotation of the bolt when tightening the nut. This restraint of the bolt will be assisted by the interfitting corrugations on the bars and bolt head.

Fig. 8 shows a detail of a modification of the bolt head holding means. Here the reinforcing bars 9' are provided with transverse grooves 24 of semi-circular cross section with the distance between centers equal to the diameter of a groove. The abutting face of the T-head of the bolt is provided with a transverse rib 25 of a size to snugly fit within the grooves 24.

The rail is adapted to rest upon a tie plate 14 which fits within a depression in the cushion block 7, and is held in position by clips 15 and 16 through which the upper ends of bolts 11 extend and are clamped by nuts 12 on the ends of bolts 11. These clips are of bent metal formed as shown in the drawings. As shown in Figure 6, the tie plate is slotted to pass the heads of the bolts 11 and has one end of each hole squared as at 18 for a purpose to be explained later.

In order that the rails may be properly set to gauge and later adjusted to take up wear, the tie plate is made slightly shorter than the recess 6 and the cushion block is provided with elongated bolt holes 17 aside from having a loose fit in the recess 6 whereby the tie plate and the upper ends of bolts 11 extending through it may move longitudinally of the tie for a short distance. For the purpose of allowing the necessary movement in adjusting the rails, the tie plate is provided with a rectangular extension 18 of the bolt holes and the inner rail clip 16 with a corresponding vertically aligned opening 19. When the clip 16 and tie plate 14 are assembled to hold the rail, a nut 20 is placed in position with its upper and lower portions in and fitting said openings and held thereby from rotation

and relative longitudinal movement. The two nuts 20 on opposite end sections of a tie are oppositely threaded and are connected together by a rod 21, having oppositely threaded ends, set in a groove 22 in the top of the tie, whereby rotation of the rod will move the tie plates and clips 16 longitudinally of the tie, towards or away from each other. The clips 15 move by frictional engagement with the tie plate or can be moved by hand to be retained in close engagement over the rail base. A recess 23 is provided at the center of the tie to provide clearance for a wrench which may be used to turn the rod 21 to adjust the gauge. The corrugations on the bolt heads and reenforcing bars 9 serve to prevent slippage of the rails longitudinally of the tie and thus help maintain the gauge perfectly. The gauge rod 21 is below the surface of the tie and protected from damage by anything dragging from a train.

The tie plate, the cushion block and the tie are each provided with elongated holes through which the T-heads of bolts 11 will readily pass so that bolts may be removed and replaced without disturbing the rail. This is of considerable importance in case a bolt should be defective or break in service.

The particular shape of my tie is very important. The diamond shaped space C is adaptable to hold ballast and prevent it from scattering, and this ballast acts to prevent longitudinal displacement of the ties. The spaces D between the outer ends of the ties provide for further ballast and allow proper tamping in order to elevate the ties to a desired level. The bottom of each tie is cut away, as shown at E in Figure 2, so that the tie is about one inch thinner in the center than at the ends, to provide proper gravity drainage.

Another important feature of the particular shape of the ties is the almost continuous support given the rail, since the large ends of the ties abut. This also provides a smooth track in case of derailment instead of the usual bumpy wooden ties with their wide spacings.

It has been found that the use of these ties reduces the number of ties per track mile by one-third to one-half.

It will be seen from the above that I have provided a novel form of concrete tie and cushioning and fastening means for the rail. It will be understood that my invention is not limited to the particular form or details shown and that various changes may be made without departing from the spirit of the invention, as set forth in the following claims.

Having thus described the invention what is claimed as new and desired to be secured by Letters Patent is:

1. A railroad tie comprising a reenforced

concrete portion, a recess in said portion, a cushion block in said recess, and means adjustable longitudinally of said tie holding said rail to said cushion block and both to 5 said concrete portion.

2. In a monolithic concrete tie, a cushion block to receive the rail, slots through the end portions of the tie and cushion block, reenforcing bars lining the slots at the bottom of the tie and T-headed holding bolts passing through said slots in said tie and cushion block, the surface of the reenforcing bars and the contacting faces of the bolts being correspondingly corrugated for longitudinal adjustment of said bolts. 10

3. In a reenforced concrete tie, means for fastening a rail thereto, comprising a cushion block, a tie plate, rail clips and T-headed bolts passing through said cushion block, tie plate and rail clips, the heads of 20 said bolts being adjustable longitudinally of the tie and means to lock said heads in adjusted position.

4. In a railroad tie, means for adjusting 25 the gauge comprising, a tie plate and rail

clip for each rail, a nut for each tie plate and rail clip and clamped therebetween, said nuts on one rail being oppositely threaded to those on the other, and a rod, correspondingly threaded connecting said opposite 30 nuts.

5. In a railroad tie, means for holding each rail to the tie, oppositely threaded means on each holding means and a threaded rod connecting said threaded means and 35 lying wholly below the surface of said tie.

6. In a reenforced concrete railroad tie, a rail cushion comprising a block of mechanically compressed self-supporting rock asphalt. 40

7. A cushion block for railroad ties comprising mechanically crushed and compressed rock asphalt having non-flowing properties.

8. A cushion block composed of mechanically compressed rock asphalt. 45

In testimony whereof I hereunto affix my signature.

WILLIE GRAHAM
